SEWING MACHINE SHUTTLE

Filed Sept. 20, 1944

UNITED STATES PATENT OFFICE

2,396,755

SEWING MACHINE SHUTTLE

William F. Shimek, Milwaukee, Wis., assignor to
United Shoe Machinery Corporation, Flemington, N. J., a corporation of New Jersey

Application September 20, 1944, Serial No. 554,868

8 Claims. (Cl. 112—233)

The present invention relates to wax thread sewing machine shuttles and, more particularly, to improvements in constructions and arrangements of parts for locking a thread supply case within the shuttle of a sewing machine and for imparting a tension to the shuttle thread while being withdrawn from a thread case in the shuttle during sewing.

In a sewing machine shuttle such as that disclosed in United States Letters Patent No. 1,905,032, granted April 25, 1933, upon an application filed in the name of Fred Ashworth, a thread supply case is provided having a locking slide movable diametrically across the end of the thread case to lock the thread case in position within the shuttle. To impart suitable tension to the shuttle thread and to lead the thread from the thread case, in the patented shuttle, the thread case has a hollow stud projecting inwardly to form a support for a supply cop inserted in the thread case and a hollow spring-pressed plunger within the stud subjects the thread leading from the cop through the stud to pressure at the point where it enters. This construction of the thread case locking and tensioning devices is effective and is advantageous in operation so long as the plunger and its actuating spring do not cause an excessive amount of wax to be stripped from the thread as it is drawn through the hollow stud. When wax stripped from the thread accumulates on the spring and tension plunger, it forms a solid cake which resists proper operation of the parts and which is likely to cause thread breakage upon the presence of irregularities in thickness of the thread. Furthermore, the thread case locking slide is held in locking position, in the patented shuttle, by a second similar hollow locking plunger, also within the hollow stud, actuated toward locking position by the opposite end of the same spring which presses the tension plunger against the thread and, if the tension spring becomes caked with hardened wax, it is impossible to release the locking slide to remove the thread case from the shuttle.

An object of the present invention is to improve the construction of a wax thread sewing machine shuttle and thread case of the type disclosed in the above-mentioned patent in such a way that accumulation of hardened wax on the thread tension and locking slide holding spring will be avoided, and otherwise to improve and perfect the manner of operation of a wax thread sewing machine utilizing such a shuttle.

In embodying the features of the present in-

vention in the illustrated shuttle, which is equipped with a removable thread supply holder forming a closure for the shuttle in the form of a casing, and having a hollow stud projecting into the shuttle casing to guide the thread to the outer side of the supply holder and a hollow plunger in the stud through which the thread leads from the supply in the holder, there is provided a spring inside the stud of the holder, shielded by the plunger from contact with the thread passing therethrough thereby preventing accumulation of wax on the spring and maintaining the parts in effective operating condition at all times. In order to obtain these results, 10 the locking slide holding and thread tension spring is coiled about the plunger rather than inside the plunger as heretofore and located within a space between the plunger and the inner surface of the hollow stud. Since the thread 15 passes through the plunger, there is no possibility of wax, stripped from the thread, accumulating on the spring when so located. In the particular form illustrated, with the use of two plungers, one for imparting tension to the thread, and the 20 other for holding the locking slide in locking position, the two plungers comprise a pair of telescoping members between which the spring is compressed.

These and other objects and features of the 25 invention will become apparent from the following description taken in connection with the accompanying drawing, in which

Fig. 1 is a view in front elevation of a shuttle, illustrating somewhat diagrammatically its relation to the needle and the work being operated upon in a machine embodying the present invention;

Fig. 2 is a detail front view of the thread holder, indicating the casing for the shuttle, the parts 30 being shown in unlocked positions;

Fig. 3 is a detail sectional view of the shuttle and thread holder, taken in section along the line III—III of Fig. 2;

Fig. 4 is a sectional plan view of the shuttle and thread holder, taken on the line IV—IV of Fig. 1, illustrating the position of the shuttle with relation to the shuttle raceway, driver and loop spreader; and

Fig. 5 is a detail view on an enlarged scale of 45 the locking slide holder and tension device shown in Fig. 4.

The shuttle illustrated in the accompanying drawing is intended to cooperate with other stitch forming devices such as a straight hook needle 50 and a loop spreader 4 and consists of a dis-

coidal shuttle casing 6, the rearward end of which is closed and the forward end of which is open to receive a thread holder 8, comprising a similarly shaped container fitting within and forming a closure for the open end of the shuttle casing. From the closed end of the thread holder, a hollow stud 10 projects inwardly so as to provide a central support for an inserted thread supply cop 12. Sliding within the stud 10, a hollow tension plunger 14 is arranged to be acted upon by a coil spring 16 tending to force the plunger against the rear wall of the shuttle casing, the plunger 14 forming a central conducting passage or guide for the thread, opening at the forward end of the thread holder with the thread leading from the interior of the thread cop between the plunger and the rear wall of the shuttle casing as in the machine of the prior patent above referred to. To produce the required sewing tension on the thread, the spring 16 exerts a suitable pressure on the plunger to resist movement of the thread through the stud.

In order to lock the thread case in position in the shuttle casing, the holder 8 is provided with a radially projecting flange 18 fitting a slot in the circular side wall of the shuttle casing, and a diametrically movable slide 20, retained within a guideway 22 in the front wall of the supply holder, is readily movable toward and from a groove 24 in the circular wall of the shuttle casing at the opposite side from the flange 18. To hold the locking slide in locking position, a second hollow plunger 26 is slidably mounted in the hollow stud 10 and is provided with a reduced end entering a hole 28 formed at the proper point in the slide 20. The slide 20 may be conveniently released by inserting a suitable tool in the hole 28 to force the plunger 26 rearwardly away from the slide, thereby allowing it to be moved into unlocking position.

In the shuttle of the Ashworth patent above referred to, the thread may come into direct contact with the locking slide holding and tension producing spring so that any excess wax on the thread may become stripped off and accumulated in the space surrounding the coils of the spring, in such a way that, when it becomes hardened, it will immobilize the spring, thereby rendering the tension ineffective and preventing release of the locking slide when it is desired to remove the thread supply holder. This difficulty is further complicated by lint or foreign materials scraped off the thread within the stud to form a reinforcing agent for the hardened wax already accumulated therein.

To prevent the accumulation of wax and other materials on the locking slide holding and tension producing spring 16 of the present invention, the spring is shielded from contact with the thread passing through the stud 10 by the tension plunger 14, and the locking slide holding plunger 26 is constructed to telescope with the tension plunger in such a way as to provide complete shielding of the spring and the space surrounding the coils of the spring from contact with the thread. The tension plunger 14 is formed with an external shoulder 30 against which one end of the spring 16 acts, and the locking slide plunger 26 has a similar shoulder 32 against which the other end of the spring acts, these shoulders being flanged to fit slidably within the stud 10 and to act as barriers against the entry of wax or other foreign materials into the space occupied by the spring. The adjacent telescoping ends of the two plungers 14 and 26 are shaped to fit closely one within the other, 75

thus preventing entry of foreign materials between the plungers. Inasmuch as the outer end of the tension plunger 14 is arranged to face in the direction in which the thread moves during sewing operations, there is no danger that the wax will be scraped off the thread by the inner end of the smaller tension plunger which is exposed to contact with the thread.

By this construction not only are the wax and foreign materials excluded from contact with the coils of the plunger actuating spring but also, when the spring and plungers are properly lubricated, the shielded space between the plungers and the inside surface of the stud 10 aids in retaining the lubricant in place so that an extremely durable and effective arrangement is provided. Furthermore, there is less possibility of wear and abrasion in the moving parts including the plungers and spring.

20 The nature and scope of the invention having been indicated and the several features having been described, what is claimed is:

1. A shuttle for shoe sewing machines, comprising a hollow casing, a removable thread supply holder forming a closure for the shuttle casing and provided with a hollow stud projecting into the casing through which the thread passes to the outer side of the holder, and a hollow plunger in the stud through which the thread leads from the supply in the holder, in combination with a spring inside the stud shielded by the plunger from contact with the thread passing through the plunger for pressing the plunger yieldingly against the thread to impart a tension thereto.

2. A shuttle for shoe sewing machines, comprising a hollow casing, a removable thread supply holder forming a closure for the shuttle casing and provided with a hollow stud projecting into the casing through which the thread passes to the outer side of the holder, and a hollow plunger in the stud through which the thread leads from the supply in the holder, in combination with a plunger actuating spring coiled about the plunger within the space between the plunger and the inside of the stud to shield the spring from contact with the thread.

3. A shuttle for shoe sewing machines, comprising a hollow casing, a removable thread supply holder forming a closure for the shuttle casing and provided with a hollow stud projecting into the casing through which the thread passes to the outer side of the holder, and a hollow plunger in the stud through which the thread leads from the supply in the holder, in combination with a plunger actuating spring coiled about the plunger within the space between the plunger and the inside of the stud to shield the spring from contact with the thread, and an external shoulder on the plunger inside the stud against which the spring acts to press the plunger against the thread.

4. A shuttle for shoe sewing machines, comprising a hollow casing, a removable thread supply holder forming a closure for the shuttle casing, and means for removably locking the thread holder to the shuttle casing, comprising a locking slide at the end of the thread holder arranged to move across the end of the holder and to engage a groove in the shuttle casing, a hollow stud through which the thread passes from the supply in the holder to the outer side thereof, and a hollow plunger in the stud, in combination with a spring inside the stud, shielded by the plunger from contact with the thread passing through the stud, for pressing the plunger yieldingly against the slide to engage a hole in

the slide and lock the slide when the slide is in locking position.

5. A shuttle for shoe sewing machines, comprising a hollow casing, a removable thread supply holder forming a closure for the shuttle casing and provided with a hollow stud projecting into the casing through which the thread passes to the outer side of the holder, a hollow plunger in the stud through which the thread leads from the supply in the holder, and means for removably locking the thread holder to the shuttle casing, comprising a locking slide in the end of the thread holder arranged to move across the end of the holder and to engage a groove formed in the shuttle casing, in combination with a 15 thread tension device including a second hollow plunger slidably mounted in the stud, telescoping with the first-mentioned plunger, and a spring for pressing said second-mentioned plunger frictionally against the thread engaging the inner surface of the shuttle casing and for pressing the first-mentioned plunger against the locking slide to engage a hole in the slide and lock the slide in locking position.

6. A shuttle for shoe sewing machines, comprising a hollow casing, a removable thread supply holder forming a closure for the shuttle casing and provided with a hollow stud projecting into the casing through which the thread passes to the outer side of the holder, a hollow plunger in the stud through which the thread leads from the supply in the holder, and means for removably locking the thread holder to the shuttle casing, comprising a locking slide in the end of the thread holder arranged to move across the end of the holder and to engage a groove formed in the shuttle casing, in combination with a 30 thread tension device including a second hollow plunger slidably mounted in the stud, telescoping with the first-mentioned plunger, and a 35 spring surrounding said plungers in the space between them and the inner surface of the stud, 40

to press one plunger yieldingly against the thread and the other yieldingly against the slide.

7. A shuttle for shoe sewing machines, comprising a hollow casing, a removable thread supply holder forming a closure for the shuttle casing and provided with a hollow stud projecting into the casing through which the thread passes to the outer side of the holder, a hollow plunger in the stud through which the thread leads from the supply in the holder, and means for removably locking the thread holder to the shuttle casing, comprising a locking slide in the end of the thread holder arranged to move across the end of the holder and to engage a groove formed in the shuttle casing, in combination with a thread tension device including a second hollow plunger slidably mounted in the stud, telescoping with the first-mentioned plunger, a spring surrounding said plungers in the space between them and the inner surface of the stud, to press one plunger yieldingly against the thread and the other yieldingly against the slide, and external shoulders on the plungers inside the stud against which the spring acts.

8. A shuttle for shoe sewing machines, comprising a hollow casing, a removable thread supply holder forming a closure for the shuttle casing and provided with a hollow stud projecting into the casing through which the thread passes to the outer side of the holder, and a hollow plunger in the stud through which the thread leads from the supply in the holder, in combination with a spring inside the stud shielded by the plunger from contact with the thread passing therethrough to impart a tension to the thread, and a second plunger arranged in surrounding relation with the first-mentioned plunger, the construction being such that the outer exposed end of the first-mentioned plunger faces in the direction toward which the thread moves during sewing operations.
